US00D866588S

(12) **United States Design Patent** (10) **Patent No.:** **US D866,588 S**
Agarwal et al. (45) **Date of Patent:** **** Nov. 12, 2019**

(54) **DISPLAY SCREEN OR PORTION THEREOF WITH GRAPHICAL USER INTERFACE**

(71) Applicant: **Lutron Technology Company LLC**, Coopersburg, PA (US)

(72) Inventors: **Rhythm Agarwal**, Bethlehem, PA (US); **Benjamin F. Bard**, Zionsville, PA (US); **Erica L. Clymer**, Northampton, PA (US); **Shenchi Tian**, Easton, PA (US)

(73) Assignee: **Lutron Technology Company LLC**, Coopersburg, PA (US)

(**) Term: **15 Years**

(21) Appl. No.: **29/663,983**

(22) Filed: **Sep. 20, 2018**

Related U.S. Application Data

(63) Continuation of application No. 29/607,668, filed on Jun. 15, 2017, now Pat. No. Des. 830,409.

(51) **LOC (12) Cl.** **14-04**

(52) **U.S. Cl.**

USPC **D14/486**; D14/492

(57)

CLAIM

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design.

1 Claim, 1 Drawing Sheet
